Application June 16, 1943, Serial No. 491,257

3 Claims. (Cl. 346—8)

1

The invention has relation to follower devices for magnetic compasses, these devices being of the type wherein a hunting action is established by successive reversals of the follower drive.

The invention consists in the novel construction and combination of parts as set forth in the appended claims.

In the accompanying drawings illustrating the invention:

Fig. 1 is a diagrammatic plan view of a compass and of certain of the associated follower elements.

Fig. 2 is a side elevation of the planetary differential gearing, the reversing means thereof and the means for operating said reversing means.

Fig. 3 is a view similar to Fig. 2, with parts omitted, taken from the opposite side, and showing the motor and associated parts.

Fig. 4 is a detail side view, taken from the same side as Fig. 2, of the planetary differential gearing, with parts removed.

Fig. 5 is a plan view of the motor drive, the differential planetary gearing and its reversing means interposed in said drive and the means for operating said reversing means, associated with integrating means of an odograph, parts being broken away.

Fig. 6 is a side elevation of said integrating means.

Fig. 7 is a plan view of the plotting mechanism of an odograph designed for operation through said integrating means.

Fig. 8 is a detail sectional view, taken longitudinally of the drive shaft, with parts broken away.

The magnetic compass and the electrical portion of the follower devices are herein shown in a preferred form, disclosed in an application for Patent Serial Number 473,355 filed by Edwin F. Britten, Jr., on January 23, 1943 now Patent 2,325,365, July 27, 1943.

The follower mechanism of the compass is controlled by photo-electric devices comprising a source of light 19 (Fig. 1) mounted within a closure 20 having a vertical slot 21 in its inner wall, light from source 19 passing through slot 21 and striking a mirror 14 fixed upon the frame which carries the compass needle 13. The closure 20, together with the photo-electric tubes to be described, are carried on a rotary plate 18 mounted within the compass casing, and upon rotary driven movement of the plate, as modified by turning movement of the conveyance in which the compass is mounted, the parts carried upon the plate will move relatively to the compass needle and mirror 14, so that the light reflected

2

from this mirror will strike one of two mirrors 23, 24, angularly disposed upon the wall of the closure 20, one at either side of slot 21, and will be reflected therefrom to one or the other of two photo-electric tubes 25, 26.

Tubes 25 and 26 have electrical connection each with one of a pair of thyratron tubes 27, 28, these tubes being biased through a rheostat 29 as shown diagrammatically in Fig. 1. Either one of these thyratron tubes, being excited by an electric current passing through the related photo-electric tube, serves to establish a circuit of comparatively high voltage through one or the other of a pair of solenoids 30, 31, which in turn control means for rotating plate 18 in one or in the other direction.

Movement transmission means in the form of planetary differential gearing to be described and having reversing means is interposed in the drive between electric motor 33, (Figs. 3 and 5) and a pinion 35 (Fig. 1) meshing with gear teeth formed in the periphery of said plate 18. Electrically energized means controlled by said follower device is provided for operating said reversing means to thereby successively reverse the direction of rotation of said transmission and of said drive to effect oscillatory hunting action as will be described. Thus the plate 18 and the parts carried thereby will be rotated first in one and then in the other direction, as controlled by the tubes 25, 26, in known manner, so that the source of light will be carried around the compass bowl in following relative movement of the needle.

35 The movement transmission means

Motor 33 has gear connection 71 with a shaft 70, the latter having driving connection with driven shaft 129 including the aforesaid planetary differential gearing interposed in the drive. 40 This planetary differential gearing has two oppositely rotating controllable members one of which is an internally toothed gear wheel 132 provided with an annular series of outer peripheral teeth 134 and supported by spokes 132' from a hub freely rotatable on the hub joining members 127 and 128 to be described. The other controllable member comprises a spur gear 133 and a wheel 133' made fast thereto by pins 133'', said wheel 133' having an annular series of peripheral teeth 134' of the same diameter as that of said first named series 134. A circular carrier plate 127 mounted to rotate freely upon drive shaft 70 has connected to its hub a gear 128 which engages gear 128' fixed to drive the shaft 129. Planet gears 126 have the shafts thereof loosely mounted

in bearings of said plate 127, the two larger of said planet gears meshing with sun gear 125 fast upon the drive shaft 70 and with said internally toothed gear 132 of the one controllable member of said transmission and the two smaller of said planet gears meshing with spur gear 133 of the other controllable member. The planetary differential gearing is provided with a reversing lever 135, fulcrumed upon shaft 136 and having opposite arms adapted respectively for engagement with the peripheral teeth 134 of the gear wheel 132 of the one controllable member of said transmission, or alternatively with the peripheral teeth 134' of the wheel 133' of the other controllable member. This reversing lever has a third arm provided at the free end thereof with opposite spaced plates 138.

The electrically energized means controlled by the followers mechanism for the purpose stated comprises two solenoids 30, 31, a lever 141 fulcrumed upon shaft 140 having opposite arms pivotally connected with the cores 30', 31' of said solenoids, one arm of said lever 141 having a finger extension 139 loosely engaged between said plates 138.

Operation

In operation, one of the solenoids 30, 31, being energized and one arm of the reversing lever 135 being engaged, say with the peripheral teeth 134 of gear 132, this controllable member of the planetary differential gearing will be held stationary, the result being that the sun gear 125 fast upon the drive shaft 70 will revolve the planet gears 126 around said sun gear in one direction, thereby, through the gearing 128, 128' driving the shaft 129 in one direction. The other of said solenoids being energized and the other arm of said reversing lever 135 being engaged with the peripheral teeth 134' of wheel 133', the other controllable member of the planetary differential gearing will be held stationary, the result being that the sun gear 125 will revolve the planet gears 126 therearound in the opposite direction, thereby, through gearing 128, 128' driving the shaft 129 in the opposite direction.

The driven shaft 129 is connected with pinion 35 by means not shown.

The gear ratios of the differential are such that the speed of the driven shaft 129 is the same in forward or in reverse drive, but, since the oppositely rotating elements 132, 133 are not driven at the same speed, they are provided with different numbers of teeth, so that a given number of teeth of either element will pass a fixed point in a given time. Thus, there will be no lag of one element, in picking up the drive, relatively to the action of the other element.

The integrator

The follower mechanism is intended for use in connection with mechanism to be controlled from the magnetic compass. This mechanism may consist of an odograph; means for charting deviations from a ship's course; automatic steering mechanism, etc. Such mechanism includes an integrator, whereby the different directional components (such as north or south and east or west) of the progressive movement of a vehicle may be integrated to effect the movement of a stylus to record upon a chart the direction and extent of such movement, that is to say, to record the path of the vehicle.

In the present application an odograph is shown, whereby a map or chart is plotted to repre-

sent the course of a conveyance. The chart table is shown in Fig. 7, wherein a holder 86 for a pen, pencil or stylus 87 is mounted on cross rods 88, 88, in known manner, movement of holder 86 and stylus 87 being determined by the travel of nuts 89 upon right angularly disposed threaded rods 91, the latter being rotated by gears 92 from said integrating means as will be explained. The cross rods 88 have at the ends thereof pinions 89 traveling upon racks 90.

The progressive movement of the conveyance is measured through the driving motion of a propeller shaft; automatic log; speedometer or other appropriate source, from which motion is transmitted through a shaft 93 (Figs. 5 and 6).

Rotation of shaft 93 is transmitted through gearing 94 to toothed cylinders 95, 96, these cylinders being driven in opposite directions at a speed proportional to the rate of advance of the conveyance.

The teeth of cylinders 95, 96 are of graded lengths, a line traced through the ends of the teeth, in the development of the cylindrical surface of the cylinder, giving a sine curve.

The pinions 97 are mounted upon splined shafts 98, located upon opposite sides of and having their longitudinal axes parallel to the cylinders 95, 96, these pinions meshing with the teeth 97' of said cylinders and being moved longitudinally thereof by means of fingers 99 of bars 99' located upon opposite sides of said shafts 98, said bars being mounted upon reciprocating plates 100, the latter being carried by links 101, pivoted at one end thereof at 101' and at their other ends pivoted upon shafts 101''. The plates 100 and consequently the pinions 97 are reciprocated by means of two rollers 102 of crank arms 102' located upon opposite sides of a shaft 103 having bearings in the stationary framing, said crank arms being disposed at right angles to each other, and said shaft 103 being driven by gears 104 from said shaft 129.

Shafts 98, 98 are provided with worms 105, 105, meshing with worm wheels 106, 106 fast respectively upon a shaft 107 and a sleeve 108, this shaft and sleeve having respective gearing connection (not shown) with the gears 92 associated with the chart table. Thus, in regulating the travel of the pencil 87, the sine curve of the graded teeth of cylinders 95, 96, together with the 90° relation of the rollers 102, 102', provide for movements of the two gears 92 in accordance with the sine and cosine components, respectively, of the travel of the conveyance.

A switch 142 (Figs. 5 and 6) is interposed in the circuit of the electric motor 33, this switch being manually operated by means of a crank handle 143, through shaft 144, arm 145, link 146 and a roller 147 of insulating material, fixed upon a rocker 148 and movable to close the spring leaves of the switch.

In order that no motion shall be transmitted to the pencil 87 of the odograph while motor 33 is not running, the gear 94 which is carried by shaft 93 is designed to be moved axially out of mesh with the next adjacent gear of the driving train. This is effected by mounting gear 94 on a splined sleeve, longitudinally movable by means of a roller 149 mounted upon a pivoted member 150 having link connection 151 with rocker 148. In order to provide for flexible movement of the adjacent devices 145-148, 150, 151, the link 151 is provided with pin and slot connection with rocker 148, and a spring 152 serves to hold the parts normally in contacting position. However,

in case the gears do not immediately mesh when it is attempted to reengage them, spring 152 will yield and rocker 148 will be allowed to come into full adjusted position. The rocker is held in either of its two adjusted positions, against suitable stops, by means of a toggle spring 153. A spring 154 may connect arm 145 and link 146 in order to lock these parts as set to inoperative position, with the pivotal connection thereof beyond dead center.

In order to provide a slip clutch effect, the gear 94 may be mounted loosely upon the slidable sleeve and pressed by spring 155 into contact with friction disks 156, one of which is fast to said sleeve.

The herein described invention is of particular advantage in controlling the action of integrating means of the type employing oppositely rotating cylinders having longitudinally extending teeth of graded lengths and axially reciprocating pinions engaging said teeth. This is because it is desired to integrate the different directional components of the progressive movement of a vehicle by infinitely fine gradations rather than by graded steps governed by the difference between the length of the teeth, to thereby record upon the chart the true direction and extent of the progressive movement of the vehicle, that is to say to more accurately record the path of the vehicle. For this purpose, the reciprocating travel of the pinions 97 should be at a uniform speed, so, for instance, that a pinion 97 which at one end of its throw shall be located half way between the ends of two adjacent teeth, will remain out of engagement with the shorter tooth for half the interval of time required to travel back and forth between the end of one tooth and that next adjacent. Thus, the pinion 97, during its reciprocation over the path stated will, over a short period of time, receive movements which are averaged between the number of teeth encountered in the plane of the longer tooth and the number encountered when this longer tooth does not act upon the pinion.

This effect could not be obtained if the known type of reversing mechanism were used, consisting of a pole reversing switch, whereby the armature of the motor is caused to rotate first in one and then in the other direction. This known mechanism gives a motion which approaches the harmonic, and the resulting travel of the integrator pinions 97 would be plotted as a succession of sine curves. On the other hand, the reversing mechanism of the present invention gives a uniform motion to the pinions 97, which may be plotted as a saw tooth curve.

I claim:

1. The combination with an odograph having a stylus and means for integrating the different directional components of the progressive movement of a vehicle to effect movement of said stylus and record the course of the vehicle, said integrating means comprising oppositely rotating cylinders having driven connection with the propeller shaft of the vehicle, said cylinders having circumferential series of longitudinal teeth of such graded lengths that an imaginary line traced through the ends of said teeth in the development of the cylindrical surface will give a sine curve, and axially reciprocating pinions meshing with said teeth; of means for accomplishing the axial reciprocation of said pinions at a uniform speed so that a pinion which at one end of its throw is located half way between the ends of two adjacent of said teeth will

remain out of engagement with the shorter tooth for half the interval of time required for its travel back and forth between the end of one tooth and that next adjacent thereto comprising photo-electrically controlled motor-driven oscillatory hunting-type follower mechanism for magnetic compasses the motor of which has rotary driving connection with said follower mechanism, said rotary driving connection comprising movement transmission means having reversing means for transmitting the drive in one or alternatively the opposite direction, said transmission having reciprocatory driving connection with said pinions, and electrically energized means controlled by said follower mechanism for operating said reversing means.

2. The combination with an odograph having a stylus and means for integrating the different directional components of the progressive movement of a vehicle to effect movement of said stylus and record the course of the vehicle, said integrating means comprising oppositely rotating cylinders having driven connection with the propeller shaft of the vehicle, said cylinders having circumferential series of longitudinal teeth of such graded lengths that an imaginary line traced through the ends of the teeth in the development of the cylindrical surface will give a sine curve, and axially reciprocating pinions meshing with said teeth; of means for accomplishing the axial reciprocation of said pinions at a uniform speed so that a pinion which at one end of its throw is located half way between the ends of two adjacent of said teeth will remain out of engagement with the shorter tooth for half the interval of time required for its travel back and forth between the end of one tooth and that next adjacent thereto comprising photo-electrically controlled motor-driven oscillatory hunting-type follower mechanism for magnetic compasses the motor of which has rotary driving connection with said follower mechanism, said rotary driving connection comprising movement transmission means having reversing means, said transmission having reciprocatory driving connection with said pinions, said reciprocatory driving connection comprising a shaft having radial arms located at right angles to each other and provided with end rollers and reciprocatory plates engaged by said rollers, said plates having means of engagement with said pinions to reciprocate the latter, and electrically energized means controlled by said follower mechanism for operating said reversing means.

3. The combination with an odograph having a stylus and means for integrating the different directional components of the progressive movement of a vehicle to effect movement of said stylus and record the path of the vehicle, said integrating means comprising oppositely rotating cylinders having driven connection with the propeller shaft of the vehicle, said cylinders having circumferential series of longitudinal teeth of such graded lengths that an imaginary line traced through the ends of the teeth in the development of the cylindrical surface will give a sine curve, and axially reciprocating pinions meshing with said teeth; of means for accomplishing the axial reciprocation of said pinions at a uniform speed so that a pinion which at one end of its throw is located half way between the ends of two adjacent of said teeth will remain out of engagement with the shorter tooth for half the interval of time required for its travel back and forth between the end of one tooth and that next adjacent thereto comprising photo-electrically controlled

motor-driven oscillatory hunting-type follower mechanism for magnetic compasses the motor of which has rotary driving connection with said follower mechanism, said rotary driving connection comprising movement transmission means having reversing means, said transmission having reciprocatory driving connection with said pinions, and electrically energized means controlled by said follower mechanism for operating said reversing means comprising two solenoids, said transmission comprising differential gearing having two oppositely rotating toothed controllable members and said reversing means comprising a lever opposite arms of which are adapted respectively to engage the teeth of one or alternatively the other of said controllable members and a second lever opposite arms of which have pivotal connection with the cores of said solenoids and one arm of which has operating connection with the first named lever.
